UNITED STATES PATENT OFFICE.

FREDERIC H. BRINKERHOFF, OF RIVERDALE, NEW JERSEY.

COIN MAGAZINE.

Application filed August 21, 1925. Serial No. 51,581.

The present invention relates to coin controlled coin magazines and is useful in various types of vending machines, coin machines, fare collectors and money changing machines, and the invention aims to provide a novel and improved device wherein coins will be received in the coin controlled magazine and are controlled for dispensing coins as such or in the form of change.

10 Another object is the provision of a coin magazine wherein the coins are individually received and held, and in which the coins will not clog or stop the machine even though the coins are thin or crooked.

15 A further object is the provision of such a device in which the coins are dispensed or paid out reversely to the entry of the coins into the magazine, that is, the last coin received is the first one discharged.

20 The invention also has for an object the improvement of the mechanism generally in its construction and in arrangement of the component elements in order that the device will be practical and efficient in use.

25 With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein—

30 Fig. 1 is a side elevation of the improved coin magazine, portions being shown in section taken on the line 1—1 of Fig. 3.

Fig. 2 is a sectional detail taken on the line 2—2 of Fig. 3.

35 Fig. 3 is a section on the line 3—3 of Fig. 1.

Fig. 4 is a section on the line 4—4 of Fig. 3.

40 Fig. 5 is a fragmentary elevation illustrating a modification.

Fig. 6 is a sectional view illustrating another modification.

45 Fig. 7 is a fragmentary elevation illustrating still another modification.

50 Fig. 8 is a fragmentary sectional view depicting a further variation.

In carrying out the invention there is provided a suitable coin holder movable in one direction when receiving coins and movable in the reverse or opposite direction after paying out or discharging coins. This mem-

ber is conveniently and preferably in the form of a wheel so as to have rotary motion, and said wheel or member 10 may be of any suitable diameter according to the capacity desired. The hub of the wheel is secured on a horizontal shaft 11 for the rotation of the wheel about the horizontal axis of said shaft, and said shaft is supported by a suitable frame 12. The rim of the wheel has radial pockets 13 opening at the opposite sides and circumference of the wheel, and a plate or disk 14 and ring 15 are secured to one side of the wheel 10 across the pockets 13, and said plate and ring are spaced apart to provide the annular slot 16 intersecting the pockets 13 at the corresponding side of the wheel. The frame 12 has a side plate 17 at the opposite side of the wheel 10 and fixed to the frame so as not to turn with the wheel, while the plate 14 and ring 15 rotate with the wheel. The plate 17 extends across the pockets 13 at that side of the wheel opposite to the plate 14, so that the plates 14 and 17 retain the coins in the pockets and prevent the coins from rolling out of said pockets at either side of the wheel. The frame 12 and plate 17 have bearings 18 and 19 in which the shaft 11 is journaled for rotation.

The coins received by the vending machine, fare collector, or other contrivance in which the coin magazine is used, drop down a chute 20 which has its lower end connected to the plate 17 at the lower portion of the wheel in order that the pockets 13 will register in succession at the corresponding side of the wheel 10 with the lower end of the chute 20, so that the coins in dropping down the chute will roll into the pockets 13 of the coin holder or wheel 10. The coins 21 may be of any denomination, and the vending machine or fare collector may have a series of the magazines for coins of different sizes or denominations.

55 The plate 17 has an arcuate flange or shield 22 overlapping the outer periphery of the wheel 10 to retain the coins in the pockets 13. One end of the shield 22 is adjacent to the chute and the other end is spaced therefrom, to provide a paying out or delivery opening 23, below which a paying out chute 24 is disposed to receive the coins paid out or discharged from the wheel 10 and convey same to a point where the coins may be taken out. The opening 23 is normally closed by a shutter 25 which is movable along the outer surface of the shield 22 away from and to-

ward the coin chute 20 in overlapping relation with that terminal of the shield 22 that is spaced from said chute. The shutter 25 is carried by a lever or arm 26 that is 5 mounted for rocking movement on the shaft 11, and said lever 26 has any suitable means, such as an eye 27, for the operation of said lever mechanically or manually for paying out the coins according to a predetermined 10 credit. The lever 26 is returned to normal position by a spring 28 and bears against a stop 29 carried by the frame 12, thereby normally holding the shutter 25 in closed position across the space or opening between the 15 ends of the shield 22, as seen in Fig. 2.

A coiled torsion spring 30 surrounds the shaft 11 and has one end secured to the bearing 18 and its other end secured to a collar 31 secured on the shaft 11, whereby said 20 spring will rotate the wheel 10 in one direction (clockwise as seen in Fig. 1). As shown, the arm 26 is located between the collar 31 and hub of the wheel 10, said lever or arm 26 being loose on the shaft.

25 An escapement is provided to permit the wheel 10 to rotate step by step under the influence of the spring 30, as the coins move in succession from the chute 20 into the pockets 13. For this purpose, an escapement lever or member 32 is pivoted to a bracket 33 carried by the frame 12, and has the dogs 34 and 35 to alternately engage annular series of ratchet teeth 36 and 37 carried by the plate 14 and ring 15, respectively. A 30 spring 38 connected to the lever 32 normally swings said lever to move the dog 35 into engagement with the ratchet teeth 37, and the lever 32 has a finger or lug 39 projecting through the slot 16 to enter the pocket 13 which is in registration with the chute 20. Each series of ratchet teeth 36—37 has one tooth for each pocket 13, and when a coin 21 rolls from the chute 20 into the registering pocket 13, the coin contacts with the 35 finger 39 and swings the lever 32 against the tension of the spring 38, to disengage the pawl or dog 35 from the corresponding tooth 37. This releases the wheel 10 so that the spring 30 rotates the wheel almost a full 40 step, and the dog 34 being moved into engagement with the corresponding tooth 36 will limit the turning movement of the wheel just slightly short of a full step of movement. The wheel having turned substantially one step will move the next empty pocket 13 into registration with the chute 20, so that the spring 38 will return the lever 32 to normal position and project the finger 39 into the empty pocket, the dog 35 returning into engagement with the wheel to engage the next tooth 37 and permit the slight turning movement of the wheel to complete the full step of movement thereof. Thus, as each coin moves into the corresponding 45 pocket of the wheel from the coin chute 20,

the wheel is advanced one step by the spring 30 and the operation of the escapement, thereby bringing the next empty pocket into registration with the chute. This filling 70 operation of the magazine is automatic, the coins operating the escapement, and the spring 30 turning the wheel 10 as the coins enter the pockets in succession.

The lever 26 carries a pawl 40 to engage the ratchet teeth 37 and move the wheel 10 75 reversely after coins have been paid out by the opening movement of the shutter 25. The pawl 40 has an arm or lug 41 that contacts with a stop 40 when the lever 26 is swung by the spring 28 to normal position, thereby swinging the pawl 40 away from the teeth 37, and said pawl 40 will therefore not interfere with the rotation of the wheel 10 by the spring 30 as the coins enter the wheel from the chute 20. When the lever 26 is swung to open the shutter 25 and permit one or more coins to drop from the pockets 13, the arm 41 moving away from the stop 42 will permit the pawl 40 to move into engagement with the ratchet teeth 37, so that 80 when the lever 26 is returned the wheel 10 will turn with said lever. The wheel 10 is returned as many steps as the number of coins discharged. Thus, if the shutter 25 is moved to discharge one coin, the pawl 40 85 will move the wheel 10 back one step to bring the emptied pocket into registration with the chute 20. If two coins are paid out, the pawl 40, during the return of the lever 26, will return the wheel 10 two steps, so that the wheel is turned backwardly, after 90 the paying out of any number of coins, whereby the last emptied pocket is brought back into registration with the chute 20.

A detent is provided for holding a coin 105 in the chute 20 when a coin has entered the pocket 13 that registers with said chute, so as to prevent clogging. This detent includes a lever 43 fulcrumed at the lower end of the chute and having an upstanding finger or lug 44 that projects upwardly into the pocket 13 that registers with the chute, when said pocket is empty. The lever 43 has a detent finger 46 projecting through a slot 47 in one side of the chute 20 adjacent the lower end of the chute, to serve as a stop for the second coin. A spring 45 connected to the lever 43 normally swings said lever to project the finger 44 upwardly into the empty pocket 13 that registers with the chute 20, thereby moving the finger 46 down out of the way so as not to obstruct the passage of a coin from the chute 20 into the registering pocket 13.

The chute 20 has a trap door 48 forming 125 the bottom of the lower end portion of the chute, and hinged, as at 49, to swing open downwardly, a weight 50 being connected to said door 48 to normally swing same upwardly to closed position, so that the coins 130

roll over said door into the pockets 13. A chute 51 leads downwardly from below the door 48 for the passage of surplus coins into a storage receptacle of any kind. The door 48, as shown, has a recess or offset 52 to receive the detent finger 46 when the detent is in normal position, so that the coins can roll over the finger 46 in passing over the door 48 into the coin pockets of the wheel 10.

10 The rotation of the wheel 10 is limited so that said wheel cannot make more than one complete revolution. This may be done by a stop lug 53 on the plate 14 to contact with one side of the lever 32 when the wheel 15 is completely filled with coins, as seen in Fig. 1, and said lug 53 contacts with the opposite side of the lever 32 when the wheel 20 is entirely empty.

In operation, the empty pocket 13 of the wheel 10 next to the last coin received by the wheel is in registration with the coin chute 20, with the escapement lever 32 moved by the spring 38 to engage the dog 35 with the corresponding tooth 37 and to project the finger 39 into said empty pocket 13. The spring 45 also swings the detent lever 43 so that the finger 44 projects upwardly into said pocket, the detent finger 46 being depressed into the recess or notch 52 so as not to interfere with the movement of a coin over the door 48 into the pocket. When a coin is dropped down the chute 20 it will roll rapidly over the door 48, so that the coin will pass over said door and into the empty pocket 13 without the door 48 being given an opportunity to swing open. The coin will press the finger 44 down and the finger 39 outwardly, as seen in Fig. 3, and this will raise the detent finger 46 into the path of the next coin, thereby preventing a second coin from following the first coin into the empty pocket of the wheel 10. This will avoid clogging or jamming of the mechanism. The finger 39 being pushed outwardly will swing the lever 32 to the position shown in Fig. 3, the dog 35 being disengaged from the corresponding tooth 37, thereby permitting the spring 30 to turn the wheel 10 almost a full step, the dog 45 34 engaging the corresponding tooth 36 to limit the movement of the wheel 10 to slightly less than a full step. The movement of the wheel will immediately bring the next empty pocket into registration with the chute 20, and the coin having been moved away from the fingers 39 and 44 will enable the springs 38 and 45 to move the levers 32 and 43 to normal position for the reception of the next coin in the empty pocket that was brought into registration with the coin chute. This operation of the mechanism is entirely automatic, and the coins will be received in the pockets 13 in succession until all of the pockets have been 60 filled, at which time the stop lug 53 will contact with the lever 32 to limit the movement of the wheel 10 to one revolution. The last coin received in the last pocket 13 of the wheel will not move the wheel, so that said coin will remain in the position shown in Fig. 3, with the detent finger 46 serving as a barrier to prevent additional coins entering the wheel. When a coin is dropped down the chute with the wheel 10 full of coins, or should the wheel 10 fail to move or advance with a coin in the pocket 13 that registers with the chute 20, the detent finger 46 will remain in raised position, so that coins dropped down the chute cannot enter the wheel and will remain on the trap door 48. A coin bearing against the finger 46 and resting on the trap door 48 will depress the trap door, and the coin will drop down the chute 51 into a surplus coin receptacle (not shown). The surplus coins are thus discharged. There is no possibility of the coins clogging or jamming in the chute 20 or wheel 10, inasmuch as the coins are dropped down the chute 20 at intervals and are individually received by the pockets 13 of the wheel, the surplus coins passing down into the surplus coin chute 51. This keeps the coins from contacting edgewise and thin and crooked coins will not interfere with the operation of the mechanism.

The coins are held individually in the pockets 13, thus providing for the convenient discharge of the coins. The last coins received by the wheel 10 are over the shutter 25, and as the shutter is swung open, the last coin received is the first coin discharged, the coins dropping from the pockets 13 into the chute 24 as the shutter 25 is moved open (toward the left as seen in Figs. 1 and 2). Thus, the movement of the lever 26 to open the shutter 25 will deliver one or more coins, and said coins may drop freely out of the pockets 13 into the paying out chute 24. When the lever 26 is moved to pay out a predetermined number of coins, the pawl 40 is moved past the same number of ratchet teeth 37, so that when the lever 26 is returned to normal position by the spring 28, the pawl 40 will turn the wheel 10 backwardly the same number of steps as coins were discharged, thereby bringing the last emptied pocket 13 into registration with the chute 20. When the lever 26 is returned, the lug or arm 41 of the pawl 40 strikes the stop 42, thereby swinging said pawl away from the teeth 37, so as not to interfere with the advance turning movement of the wheel 10 by the spring 30 when the coins are fed into the wheel. The spring 28 exerts sufficient power to overcome the force of the spring 30 so that the wheel 10 is moved backwardly with the lever 26 under the influence of the spring 28 against the influence of the spring 30.

Fig. 5 illustrates a modification. Thus,

the ratchet teeth 37^a are disposed at the inner periphery of the rim of the wheel 10^a, and only one set of ratchet teeth is necessary. The escapement lever 32^a has its opposite ends or dogs arranged to alternately engage the teeth 37^a for the step by step movement of the wheel. The lever 32^a is controlled by an electromagnet 55 disposed in an electrical circuit 56 with the battery 57 or other source of energy and the contacts 58. Said contacts are so arranged that when the detent lever 43^a is swung downwardly by the movement of a coin into the wheel, the lever 43^a bridges the contacts 58, thereby closing the circuit 56 and energizing the magnet 55 so that the lever 32^a is moved to permit the coin holding wheel to advance almost a full step. When the wheel has advanced substantially one step, the lever 43^a being restored to normal position will open the circuit 56 and deenergize the magnet 55 so that the escapement lever 32^a is returned to normal position the wheel then completing its full step of movement. The pawl 40^a which is pivoted to the lever or arm 26^a that carries the shutter 25^a is also engageable with the ratchet teeth 37^a, and has a cam finger 41^a which rides over a pin or lug 42^a when the shutter 25^a is returned to normal closed position, thereby raising the pawl 40^a away from the teeth 37^a so as not to interfere with the advance movement of the coin wheel when it is being advanced in receiving coins.

Fig. 6 illustrates another modification wherein the pockets 13^b of the wheel 10^b are open at their inner as well as their outer ends, so that the coins may drop from the coin chute 20^b downwardly into the pockets at the lower portion of the wheel, and the pockets may be closed at both sides of the wheel. The outer ends of the pockets 13^b are closed by the shield 22^b and shutter 25^b, the same as hereinbefore described, and in order to prevent the coins from dropping out of the pockets at the upper portion of the wheel, flap members 60 are pivoted within the wheel beyond the inner ends of the partitions between the pockets 13^b, and are free to swing downwardly by gravity. Thus, the members 60 are in depending positions at the lower portion of the wheel, so as not to interfere with the downward movement of a coin from the chute 20^b into the empty pocket below and registering with said chute. As said members 60 are moved upwardly they come into overlapping relation, as seen at the left side of Fig. 6, and said members remain in overlapping relation at the upper portion of the wheel, so as to support the coins in the pockets.

Fig. 7 illustrates a spiral or helical construction of the coin magazine, which may be of any desired length when a large capacity is wanted. Thus, a helix 10^c having the

pockets for the coins is connected by spokes 10^c with the shaft 11^c, and said helix is movable along a helical path, when rotated in opposite directions. The helix 10^c moves within the stationary helical shield 22^c that is disposed around the helix, and which has a flange 17^c overlapping one side of the helix, and to which the coin chute 20^c is secured so that the pockets of the helix move in succession past the coin chute, the same as with the wheel type of magazine, the operation being substantially the same. The helix 10^c has the ratchet teeth 37^c forming part of the escapement of the kind shown in Fig. 5, the pawl 32^c being operated by an electromagnet 55^c. The shutter 25^c, lever 43^c and its finger 44^c, trap door weight 50^c and chute 51^c are substantially the same as shown in Figs. 1, 2, 3 and 4.

Fig. 8 illustrates a slide 10^d having rectilinear movement instead of circular movement and having the coin pockets 13^d. The pockets are movable past the coin chute 20^d, the same as hereinbefore described, and the slide 10^d moves over a shield 22^d having the discharge opening 23^d controlled by the shutter 25^d to pay out the coins into the chute 24^d. A lever 43^d is also shown having the finger 44^d substantially as hereinbefore described. The operation is substantially the same as that of the construction shown in Figs. 1, 2, 3 and 4, excepting that the slide 10^d has a rectilinear instead of a curvilinear movement.

Having thus described the invention, what is claimed as new is:

1. A coin magazine comprising movable coin holding means having a series of coin receiving pockets, a coin chute with which said pockets register in succession, means operable for automatically advancing said coin holding means step by step and controlled by the coins as the coins move from the chute into the pockets, and means for paying out one or more of the last coins received by said pockets and returning the coin holding means a corresponding number of steps.

2. A coin magazine comprising movable coin holding means having a series of coin receiving pockets, a coin chute with which said pockets register in succession, means for moving said coin holding means in one direction, an escapement controlling such movement of the coin holding means for the step by step movement of said coin holding means and controlled by the coins as the coins move in succession from the chute into the pockets, and means for paying out one or more of the last coins received by the coin holding means and returning said coin holding means in the opposite direction a corresponding number of steps.

3. A coin magazine comprising movable coin holding means having a series of coin

- receiving pockets, a coin chute with which said pockets register in succession, automatic means operable for advancing said coin holding means step by step controlled by the movement of the coins from the chute into the pockets, and means for paying out the coins from said pockets. 70
4. A coin magazine comprising movable coin holding means having a series of coin receiving pockets, a coin chute with which said pockets register in succession, means for moving said coin holding means in one direction, an automatic escapement controlling such movement of the coin holding means for the step by step movement of said coin holding means and controlled by the coins as the coins move in succession from the chute into the pockets, and means for paying out the coins from said pockets. 75
- 20 5. A coin magazine comprising a movable coin holding member having a series of coin receiving pockets and ratchet teeth, a coin chute with which said pockets register in succession, means for moving said member in one direction, an escapement member co-operable with said teeth, automatic controlling means for said escapement member operable by the coins as they move from the chute into said pockets so that said member is moved step by step by the firstnamed means, and means for paying out the coins from said pockets. 80
- 30 6. A coin magazine comprising a movable coin holding member having a series of coin receiving pockets and ratchet teeth, a coin chute with which said pockets register in succession, means for moving said member in one direction, an escapement member co-operable with said teeth, automatic controlling means for said escapement member operable by the coins as they move from the chute into said pockets so that said member is moved step by step by the firstnamed means, and means for paying out one 85 or more of the last coins received by said pockets and returning the coin holding member a corresponding number of steps. 90
- 40 7. A coin magazine comprising movable coin holding means having a series of coin receiving pockets, and means operable for paying out one or more of successive coins with a single operation and moving said means, to complete the operation, a corresponding number of steps in succession so 95 that other coins in said means take the places of those paid out. 100
- 50 8. A coin magazine comprising movable coin holding means having a series of coin receiving pockets, a shield having an opening through which the coins may discharge from said pockets, a shutter normally closing said opening and movable to permit one or more of the coins to discharge from said pockets, and means operable with said shutter for moving the firstnamed means a 105
- 55 number of steps corresponding to the number of coins discharged, when the shutter is closed, so that coins in the firstnamed means take the places of those coins that were discharged. 110
- 60 9. A coin magazine comprising a movable coin holding member having a series of coin receiving pockets and ratchet teeth, a shield for said member having an opening through which the coins may discharge from said pockets, a shutter normally closing said opening and movable in one direction for the discharge of one or more of said coins from the pockets, and a pawl movable with said shutter and engageable with said ratchet teeth during the closing movement of the shutter to move said member a number of steps corresponding to the number of coins discharged so that coins in said member take the places of those discharged. 115
10. A coin magazine comprising movable coin holding means having a series of coin receiving pockets, a coin chute with which said pockets register in succession, means operable for advancing said coin holding means step by step as the coins move from the chute into the pockets, a shield for holding the coins in said pockets and having an opening through which the coins may discharge from said pockets, a shutter normally closing said opening and movable in the direction that the coin holding means is advanced for discharging one or more of the last coins received by said pockets, and means movable with said shutter for moving the coin holding means reversely, when the shutter is closed, a number of steps corresponding to the number of coins discharged. 120
11. A coin magazine comprising a movable coin holding member having a series of coin receiving pockets, a coin chute with which said pockets register in succession, means for moving said coin holding member in one direction, an escapement controlling such movement of said member for the step by step movement of said member as coins move in succession from the chute into the pockets, a shield for retaining the coins in said pockets and having an opening through which the coins may discharge from said pockets, a shutter normally closing said opening and movable in the aforesaid direction for paying out one or more of the last coins received by said pockets, and means movable with said shutter for moving said coin holding member in the opposite direction, when said shutter is closed, a number of steps corresponding to the number of coins discharged from the pockets when the shutter was opened. 125
12. A coin magazine comprising movable coin holding means having a series of coin receiving pockets, a coin chute with which said pockets register in succession, means operable for advancing said coin holding 130

means step by step as coins move from the chute into the pockets, and a trap door over which the coins move from the chute into said pockets and arranged to swing open 5 when a coin remains thereon so as to discharge such coin.

13. A coin magazine comprising movable coin holding means having a series of coin receiving pockets, a coin chute with which 10 said pockets register in succession, means operable for advancing said coin holding means step by step as the coins move from the chute into the pockets, and a detent operated by a coin entering the pocket which 15 registers with the chute for stopping the next coin following in the chute until said coin holding means has moved one step to bring the next empty pocket into registration with the chute.

14. A coin magazine comprising movable coin holding means having a series of coin receiving pockets, a coin chute with which said pockets register in succession, means operable for advancing said coin holding 25 means step by step as the coins move from the chute into the pockets, a detent operated by a coin entering the pocket which registers with the chute for stopping the next coin following in the chute until said coin holding means has moved one step to bring 30 the next empty pocket into registration with the chute, and means for discharging the lastnamed coin if the detent prevents movement thereof into the coin holding means.

15. A coin magazine comprising movable coin holding means having a series of coin receiving pockets, a coin chute with which said pockets register in succession, means operable for advancing said coin holding 40 means step by step as the coins move from the chute into the pockets, a detent operated by a coin entering the pocket which registers with the chute for stopping the next coin following in the chute until said coin holding means has moved one step to bring 45 the next empty pocket into registration with the chute, and a trap door over which the coins move from the chute into the pockets and so arranged that a coin stopped by the 50 detent rests on the trap door and will swing the trap door open to discharge such coin.

16. A coin magazine comprising movable coin holding means having a series of coin receiving pockets, a coin chute with which 55 said pockets register in succession, means operable for advancing said coin holding means step by step as coins move from the chute into the pockets, and means for discharging the coins from the chute when said 60 coin holding means refuses to receive a coin.

17. A coin magazine comprising movable coin holding means having a series of coin receiving pockets, a coin chute with which

said pockets register in succession, means operable for advancing said coin holding means 65 step by step as the coins move from the chute into the pockets, and a detent having a finger to project into the pocket which registers with the chute and a detent finger movable in the chute, the lastnamed finger 70 being moved into the path of a second coin following a coin that has moved from the chute into the registering pocket when the firstnamed finger is moved by said coin entering the pocket. 75

18. A coin magazine comprising movable coin holding means having a series of coin receiving pockets, a coin chute with which said pockets register in succession, means operable for advancing said coin holding 80 means step by step as coins move from the chute into the pockets, a detent having a finger to project into the pocket which registers with the chute and a detent finger movable in the chute, the lastnamed finger 85 being moved into the path of a second coin following a coin that has moved from the chute into the registering pocket when the firstnamed finger is moved by said coin entering the pocket, and a trap door arranged to be opened by a coin stopped by said detent finger to permit said coin to be discharged from the chute. 90

19. A coin magazine comprising movable coin holding means having a series of coin receiving pockets, a coin chute with which said pockets register in succession, and coin controlled means operable for advancing said coin holding means step by step as coins move from the chute into the pockets. 95

20. A coin magazine comprising movable coin holding means having a series of spaced coin receiving pockets, a coin chute with which said pockets register, and coin controlled means operable for moving said 105 pockets to register with said chute.

21. A coin magazine comprising movable coin holding means having a plurality of coin receiving pockets, a coin chute with which said pockets register, coin controlled 110 means operable for advancing said coin holding means to register with said chute, and means for paying out the coins from said pockets.

22. A coin magazine comprising movable 115 coin holding means having coin receiving pockets, a coin chute with which said pockets register in succession, coin controlled means for advancing the coin holding means, and means operable for paying out either 120 a single coin or a plurality of coins simultaneously from said pockets.

In testimony whereof I hereunto affix my signature.

FREDERIC H. BRINKERHOFF.
